LUBRICATING APPARATUS

Ernest W. Davis, Oak Park, Ill., assignor to
 Stewart-Warner Corporation, Chicago, Ill., a
 corporation of Virginia

Application January 22, 1937, Serial No. 121,741

10 Claims. (Cl. 221—47.1)

My invention relates generally to lubricating apparatus, and more particularly to improvements in high pressure lubricant compressors and in the means for priming the high pressure cylinders thereof.

It is an object of my invention to provide a high pressure lubricant compressor which may be attached to a lubricant containing drum and which will be effective in withdrawing all of the lubricant from the drum.

A further object is to provide an improved means for collecting and conveying lubricant to the pumping cylinder of a lubricant compressor.

A further object is to provide an improved power operated lubricant compressor having improved priming means.

Other objects will appear from the following description, reference being had to the accompanying drawings, in which:

Fig. 1 is an elevational view of the lubricant compressor, the high pressure cylinder and the priming means being shown in central vertical cross section;

Fig. 2 is a sectional view showing particularly the fluid motor and operating mechanism and taken on the line 2—2 of Fig. 1;

Fig. 3 is a side elevational view of the head of the lubricant compressor taken on the line 3—3 of Fig. 2;

Fig. 4 is a horizontal sectional view taken on the line 4—4 of Fig. 3;

Fig. 5 is a horizontal sectional view taken on the line 5—5 of Fig. 1;

Fig. 6 is a horizontal sectional view taken on the line 6—6 of Fig. 2; and,

Fig. 7 is a fragmentary sectional view taken on the line 7—7 of Fig. 3.

The compressor of my invention is, as shown in Fig. 1, adapted to be mounted directly upon a drum 10 forming an original container for the lubricant to be discharged by the compressor, and the compressor is therefore carried by a cover 12 which rests upon the top of the drum 10 and may be secured thereto by a plurality of clamping screws 14. A compressor body casting 16 is secured in a central upwardly extending flange 18 of the cover 12 and is internally threaded to receive the priming cylinder 20 which is in the form of a long tube extending substantially to the bottom of the drum. The casting 16 is hollow and has a vertical bore 22 to receive a high pressure cylinder 24, the ends of which are threaded and extend beyond the casting 16, being secured in place in said casting by a nut 26 and elbow fitting 28. The cylinder 24 is provided with a

plurality of inlet openings 30, one of which is opposite an opening 32 (Fig. 6) formed in the wall of the casting 16 and which leads to a cylinder 34. A cup leather piston 36 is reciprocable in the cylinder 34, being normally urged toward the opening 32 by a compression coil spring 38 which seats against an apertured cap 40 threaded in the outer end of the cylinder. The piston 36 with its cylinder 34 thus forms a yielding lubricant storage reservoir adjacent the inlet to the high pressure cylinder to aid in rapid priming of the latter. A pair of check valve fittings 42 and 44 are connected in series to the outlet elbow 28, the discharge hose 46 being connected to the check valve fitting 44.

A plunger 48 is reciprocable in the cylinder 24 and at the lower limit of its stroke, as shown in Fig. 1, extends into the vertical bore of the outlet elbow 28. The upper end of the plunger is suitably connected for actuation by a piston rod 50, which, at its upper end, has a suitable piston 52 reciprocable in a cylinder 54. A cylinder head 56 closes the upper end of the cylinder and the lower end of the cylinder is closed by a casting 58. The head 56 and casting 58 are each provided with annular grooves to receive the cylinder 54, suitable gaskets being provided to form an airtight seal. The head 56 is held in position by a plurality of tie bolts 60 which are threaded in the casting 58 and the upper ends of which project through ears formed integrally with the head 56. The piston rod 50 is provided with a suitable packing held in place by a packing gland 62. The casting 58 has three ribbed tension elements 64 which join the head portion 58 of the casting 35 with the base portion 66 thereof, the base portion being suitably secured to the casting 16 by cap screws 68.

A valve mechanism 70 is suitably secured to the head portion of the casting 58 and is adapted, during the operation of the compressor, alternately to admit compressed air to the opposite ends of cylinder 54 to cause reciprocation of the piston 52. This valve mechanism is more fully disclosed in my prior Patent No. 2,022,232, granted November 26, 1935. The valve is controlled by a reciprocating stem 72, which is operated by a valve actuator 74 slidably mounted on a rod 76 and which is connected to the piston rod 50 by means of a pin 78. Compression springs 80 and 82 serve to transmit the movement of the valve actuator 74 to the valve stem 72 so that the latter may have a snap action. Compressed air is supplied to the motor through a hose 84, the air being filtered through a strainer 86 prior to

flowing into an oiler 88 from which the air flows into the valve mechanism 70.

A shaft 90 is mounted for rotation in bearings 92 and 94, preferably formed integrally from the arms 64 of the casting 58, the shaft having a bevel gear 96 keyed or otherwise suitably secured thereto. The bevel gear is intermittently rotated by means of a pawl 98 pivotally mounted upon a stud 100 carried at the end of an arm 102 which forms part of a centrally pivoted lever 104 which has a second arm 106. The lever 104 bears upon the shaft 90 and pivots freely thereon. The arm 106 has an open end slot 108 formed therein to engage a roller 110 which is rotatably mounted on the pin 78. Thus, upon the downward movement of the piston rod 50, the lever 104 will be swung clockwise (Fig. 3), whereupon the pawl 98 will engage the teeth of the bevel gear 96 (as shown in Fig. 7) and rotate the bevel gear through an angle of approximately 60°.

The bevel gear 96 meshes with a bevel pinion 112 keyed or otherwise secured to a shaft 114 which is mounted for rotation in a bearing 116 formed integrally with the casting 16. A helical conveyor blade 118 is welded or otherwise suitably secured to a tube 120 which is secured to the shaft 114 by a pin 122. A pair of spirally shaped collector blades 124 are secured to the lower end of the tube 120 and are rotated thereby closely adjacent the bottom of the drum 10 and thus urge the lubricant toward the opening at the lower end of the cylinder 20. Further to facilitate the flow of lubricant toward the inlet end of the cylinder 20, the collector blades 124 are provided with impeller blades 126 which may be formed integrally with the blades 124 and are arranged to feed the lubricant downwardly into the path of the collector blades.

40 A follower plate 128 has a central annular guide flange 130 adapted to engage and slide freely upon the cylinder 20 and has a peripheral flange 132 cooperable with the cylindrical wall of the drum 10. The follower preferably has a raised central portion 134 to provide clearance for the collector blades 124 and impeller blades 126 when the follower is at the lower end of its stroke, so that substantially all of the lubricant contained in the drum may be drawn therefrom. 45 By virtue of the use of the follower plate, the lubricant within the drum will flow evenly toward the inlet opening at the end of the cylinder 20 and there will be no danger of the air piercing the body of the lubricant and forming a channel 50 which would prevent proper flow of lubricant into the cylinder 20.

In normal operation, the hose 84 will be connected to a suitable supply of compressed air and will remain connected thereto throughout 60 a series of lubricating operations. The discharge hose 46 will ordinarily have a suitable manually operated control valve at the extremity thereof for controlling the discharge of lubricant therefrom to the bearing or other part requiring lubrication. When said control valve is opened, the pressure in the discharge conduit will be relieved and the air motor piston 52 commence reciprocating, due to the decrease in the resistance offered to movement of the plunger 48. The air 65 motor will continue operating as long as the lubricant pressure in the discharge conduit is insufficient, when exerted upon the cross sectional area of the plunger 48, to balance the pressure of the compressed air upon the face 70 of the piston 52.

Upon each reciprocatory stroke of the piston 52, the pawl 98 will engage the bevel gear 96 and advance the bevel gear through a predetermined angle, thus rotating the bevel pinion 112 and the helical blade 118 through a substantially greater angle due to the ratio of the diameters 5 of the bevel gear 96 and the bevel pinion 112. The rotation of the impeller blades 126 and collector blades 124 will cause gradual feed of the lubricant toward the open lower end of the cylinder 120. The helical blade 118 will act upon the lubricant as a screw conveyor and discharge the lubricant into the chamber formed in the casting 16, and through the port 32 into the expansible reservoir 34.

Near the end of the upward stroke of the piston 52 and plunger 48, the latter will uncover the inlet ports 30 and the spring 38 behind the piston 36 will advance the latter to force lubricant into the high pressure cylinder 24. The various parts 20 of the compressor are so proportioned that more lubricant will be elevated by the helical conveyor blade 118 than can be discharged by the high pressure plunger 48. Thus, the lubricant which will be more or less compressed will be stored 25 under slight pressure within the hollow casting 16, and thus be readily available for rapidly priming the high pressure cylinder 24. The slight clearance between the helical blade 118 and the internal bore of the cylinder 20 will, 30 however, be sufficient to prevent the building up of excessive pressure in the casting 16.

After all of the lubricant has been withdrawn from the drum, clamping screws 14 may be loosened and the cover 12, together with all the pumping mechanism, readily removed from the drum and inserted and attached to a different drum full of lubricant. In this way, the lubricant may be efficiently removed from the original containers without subjecting it to the possibility of contamination, dust, dirt, and foreign matter.

Although the compressor may be used with various kinds of lubricant, it is designed particularly for use with relatively viscous greases. 45 Such greases do not flow readily, especially at low temperatures. The presence of a large air pocket in the grease might cause the screw conveyor to become "air bound" were it not for the provision of the blades 124 and 126. These blades tend to break up any air pockets which may be present in the grease and to feed the grease toward the inlet end of the screw conveyor, thus assuring the presence of sufficient lubricant in the screw conveyor to cause the latter to feed the lubricant to the high pressure cylinder at a rapid rate and at a pressure high enough quickly to prime the latter. The blades 124, 126 also agitate the grease and to some extent make the grease less viscous so that it will more readily flow through the screw conveyor and into the high pressure cylinder.

While the embodiment of my invention herein shown and described is admirably adapted to fulfill the objects primarily stated, it is to be understood that it is not intended to confine the invention to the specific form herein disclosed, for it is susceptible of embodiment in various forms, all coming within the scope of the claims which follow.

I claim:

1. In a high pressure lubricant compressor having a lubricant container, a cover therefor, a high pressure pumping mechanism including a plunger mounted upon said cover, fluid pressure motor 75

positions in each of which a receiving means is in alignment with a spindle, said unit comprising a disc the periphery of which is provided with notches corresponding in number to and radially aligned with said spindles, a stationary latch to coact with said notches, said latch being ver-

5 tically elongated to maintain engagement with said notches during reciprocation of the unit, means to rotate said spindles and means to reciprocate said unit.

5

MAX GEORGE FIEDLER.
